UNITED STATES PATENT OFFICE.

JOSEPH O. CHARPENTIER, OF CONCORD, NEW HAMPSHIRE.

INDICATOR ATTACHMENT FOR FIRE-BUCKET SUPPORTS.

1,191,667.

Specification of Letters Patent. Patented July 18, 1916.

Application filed December 22, 1915. Serial No. 68,250.

To all whom it may concern:

Be it known that I, JOSEPH O. CHARPENTIER, a citizen of the United States, residing at Concord, in the county of Merrimack and 5 State of New Hampshire, have invented new and useful Improvements in Indicator Attachments for Fire-Bucket Supports, of which the following is a specification.

This invention has for its object to provide means for indicating to an observer, standing on the floor of an apartment, the quantity of water in a fire bucket hung from an elevated support and located higher than the observer's head.

15 It is customary in machine shops and other establishments to hang fire buckets from supporting hooks which are elevated to locate the buckets out of the way above the heads of the occupants. The quantity 20 of water in a fire bucket thus located cannot be easily determined by a person standing on the floor.

Hooks adapted to be attached to elevated supports and fire buckets adapted to be hung 25 thereon are standard parts of the equipment of various establishments.

My invention as here illustrated is embodied in an attachment comprising a guide having means whereby it may be quickly and 30 firmly secured to an ordinary hook of standard form without change or modification of the hook; the guide when thus secured standing vertically over the bottom of a bucket hung from the hook without engagement 35 with the bucket, and a float adapted to slide on the guide and to be supported by water in the bucket, so that the projection of the float above the bucket indicates to an observer on the floor the quantity of water in 40 the bucket.

Of the accompanying drawings forming a part of this specification: Figure 1 represents a perspective view showing a hook and a bucket, both of standard form, and an 45 indicating attachment embodying my invention secured to the hook; Fig. 2 represents a sectional view of the attachment.

The same reference characters indicate the same or similar parts in all the views.

50 In the drawings, 12 represents a support for a fire bucket 13, said support as here shown being a hook having a bail-engaging portion formed to engage the bail of a bucket, a tapered shank portion, and a base 55 portion adapted to be secured or bolted to a wall.

My improved attachment includes a guide 14 having support-engaging means adapting the guide to be rigidly supported in a vertical position with its upper portion above 60 the bucket-containing space and its lower portion within said space and above the bottom of the bucket, and a float 15 adapted to slide vertically on the guide and to be supported by water in the bucket. I prefer to 65 embody the support-engaging means in an angular arm on the upper end of the guide, said arm including a horizontal portion 16 and a vertical portion 17, the guide and arm being preferably formed by bending a flat- 70 sided metal strip as shown by the drawings.

The vertical arm portion 17 has an eye 19 formed to have a close driving fit on the tapered shank portion of the hook 12, said eye being so formed that it is capable, by 75 suitable manipulation, of sliding along the curved bail-engaging portion and onto the shank portion of the hook. The eye 19 may be surrounded by a flange 20 formed to have 80 a relatively wide bearing on the shank portion, thus preventing the arm portion 17 and the guide from tipping from a vertical position. The float 15 is preferably an elongated sheet metal tube closed at its lower end by a bottom 21, and having at its upper end a 85 fixed head 22 containing a slot 23 loosely surrounding the guide 14.

The guide may be provided with scale marks, as shown by Fig. 1, coöperating with the head 22 in indicating the distance between the head and the ends of the guide. The head is preferably inclined relatively to the guide and the body of the float, so that the intersection of the head and guide may be readily observed by a person looking upwardly from a point at one side of the bucket. The head is provided with a runner 25, preferably formed as a flattened tube loosely surrounding the guide and enabling the float to slide freely on the guide 100 without binding thereon. The guide is provided at its lower end with a stop preferably formed by prongs 26 integral with and bent outwardly from the guide, to prevent separation of the float from the guide. 105

The attachment is entirely independent of the bucket, and does not interfere with either the removal of the bucket from the hook or its replacement thereon. When the bucket is removed from the hook the attachment 110 remains in position, the float being supported in its lowest position by the stop

prongs 26. When the bucket is replaced after being charged with water, the float is raised by the water to an operative height determined by the height of the water.

5 It will now be seen that the described attachment may be quickly and conveniently engaged with a bucket support in position to indicate the quantity of water therein, no change or adaptation of the support and 10 no connection between the attachment and the bucket being required.

The buoyancy and length of the float are preferably such that when the bucket is properly filled the head of the float will 15 project considerably above the rim of the bucket.

The float may be provided with an inscription, such as "Water Wanted", so arranged that when the contents of the bucket 20 require replenishment the inscription will be at or near the rim of the bucket.

Having described my invention, I claim:

1. An indicator for fire buckets, comprising a guide having support-engaging means 25 adapted to rigidly hold the guide in a vertical position with its upper portion above a bucket-containing space and its lower portion within said space, and a float adapted to slide vertically on said guide and 30 to be supported by water in a bucket occupying said space, the guide being provided with a stop limiting downward movement of the float thereon, whereby, when the bucket is removed, the float is supported independently in position to be raised by 35 water in a replaced bucket.

2. An indicator attachment comprising a guide having means for engaging the shank portion of a bucket-supporting hook, the 40 engagement of said means and shank rigidly supporting the guide in a vertical position with its upper portion above the bucket-containing space below said hook and its lower portion within said space, and a float 45 adapted to slide vertically on said guide and to be supported by water in said bucket, the guide being provided with a stop whereby,

when the bucket is removed, the float is supported independently in position to be raised by water in a replaced bucket. 50

3. An indicator attachment comprising a guide having means for frictionally and detachably engaging the tapering shank portion of a bucket-supporting hook, said means including an eye formed to have a driving fit on said shank portion, the guide being rigidly supported independently of the bucket by the engagement of said means and shank with its upper portion above the bucket-containing space below said hook, and its lower portion within said space, and a float adapted to slide vertically on said guide and to be supported by water in said bucket, the guide being provided with a stop whereby, when the bucket is removed, the float is supported independently in position to be raised by water in a replaced bucket. 65 65

4. An indicator attachment comprising a guide having means for engaging a bucket support, and adapted to stand vertically 70 over the bottom of a bucket hung on said support, and a float adapted to slide vertically on said guide and to be supported by water in said bucket, said float being provided with a slotted head constituting an indicating member coöperating with the guide and inclined relatively to the guide to enable the indication to be read from a lower point. 75

5. An indicator attachment comprising a 80 guide having means for engaging a bucket support, and adapted to stand vertically over the bottom of a bucket hung on said support, and a float adapted to slide vertically on said guide and to be supported by 85 water in said bucket, said float being provided with a slotted head constituting an indicating member coöperating with the guide, and the guide being provided with a stop within the float to prevent separation 90 of the float from the guide.

In testimony whereof I have affixed my signature.

JOSEPH O. CHARPENTIER.
